UNITED STATES PATENT OFFICE.

HARRY L. BEACH, OF COSHOCOTON, OHIO, ASSIGNOR TO CHARLES E. HIRES CO., OF PHILADELPHIA, PENNSYLVANIA.

DESIGN FOR A STAMPED-METAL FRAMED PICTURE.

42,266.

Specification for Design.

Patented Mar. 12, 1912.

Application filed November 30, 1909. Serial No. 530,697. Term of patent 14 years.

To all whom it may concern:

Be it known that I, HARRY L. BEACH, a citizen of the United States, residing at Coshocton, in the county of Coshocton and State of Ohio, have invented a new, original, and ornamental Design for a Stamped-Metal Framed Picture, of which the following is a specification.

Reference is had to the accompanying drawing, in which:

Figure 1 is a perspective view of a stamped metal framed picture, showing my new and ornamental design. Fig. 2 is a fragmentary view of the upper portion of the same, the picture being omitted.

As shown in the drawing the leading or material feature of the design resides in an elliptical plate or sheet, having a depressed elliptical plane picture bearing surface and provided with a wide marginal elliptical border portion 1 and a narrow elliptical bead 2, inclosing the plane elliptical picture surface 3. The wide elliptical border is

transversely concave and has a round or cylindrical bead at its outer edge, and is provided at its inner edge with an inclined elliptical connecting portion 5, forming a bevel and extending from the broad marginal border to the elliptical bead and rearwardly off-setting the bead from the plane of the marginal border. The face of the narrow bead is flat and extends inwardly from the inclined or bevel connecting portion 5, and is provided at its inner edge with an inclined connecting bevel portion 6, which depresses the elliptical picture bearing surface 3 below or in rear of the plane of the face of the narrow bead.

I claim:—

The ornamental design for a stamped metal framed picture, as shown and described.

HARRY L. BEACH.
